UNITED STATES PATENT OFFICE

EDWARD A. RUSSELL, OF CHICAGO, ILLINOIS, ASSIGNOR TO VAPOR CAR HEATING COMPANY, INC., OF CHICAGO, ILLINOIS, A CORPORATION OF NEW YORK

VAPOR REGULATOR

Application filed November 24, 1930. Serial No. 437,870.

This invention relates to new and useful improvements in a vapor regulator for controlling the flow of vapor or steam to the radiators of a railway car heating system.

5 Vapor regulators of this type, which are well known in the art, comprise a valve located in the steam supply line, and a thermostatic element for controlling the valve, said thermostatic element being subject to the 10 temperatures of the fluids returned from the radiators. The vapor regulator is positioned beneath the car so as to be exposed to outside air currents, and the thermostatic element is usually substantially enclosed in 15 a housing through which the returned steam, air and condensate passes before flowing or dripping out through an opening or openings in the lower end of the housing. This housing serves to enclose the thermostatic 20 element in a surrounding envelope of the returned fluids so that it will promptly respond to the temperature thereof, and also serves to protect the thermostatic element from the outside air current, particularly 25 when the car is in motion. However, in vapor regulators, as heretofore constructed, there has been a tendency for outside air to flow or be drawn in through the outlet opening or openings in the bottom of the vapor 30 regulator, thus causing undesired temperature changes in the space directly surrounding the thermostatic element and impairing the proper functioning thereof.

According to the present invention, the 35 outlet passages in the closure at the lower end of the vapor regulator, are so arranged as to minimize the exposure at the lower end of the thermostat chamber and hinder the inward passage of air, and an inwardly and downwardly projecting deflecting flange is provided around the outlets to induce an outward suction through these outlet passages, particularly when the car is in motion.

40 The general object of this invention is to provide certain new and useful improvements in a vapor regulator, such as briefly referred to hereinabove, and disclosed more in detail in the specifications which follow.

45 Another object is to provide an improved

form of closure for the lower end of a vapor regulator.

Another object is to provide improved means for preventing the in-flow of air through the outlet opening at the bottom of 55 the vapor regulator.

Another object is to provide improved means for creating an outward suction from the thermostat chamber of the vapor regulator.

Other objects and advantages of this invention will be more apparent from the following detailed description of one approved form of apparatus embodying the principles 60 of this invention.

In the accompanying drawings:

Fig. 1 is a central vertical section through the complete vapor regulator.

Fig. 2 is an end elevation of the vapor regulator, parts thereof being shown in central vertical section, taken substantially at right angles to the section shown in Fig. 1.

Fig. 3 is a perspective view of the closure member.

Fig. 4 is a horizontal section, taken substantially on the line 4-4 of Fig. 2.

Fig. 5 is a plan view of the closure member.

The main casting or supporting frame 1 comprises an upwardly extending arm 2, in which the high and low pressure supply 80 chambers are formed, and a horizontally projecting arm 3 from which the thermostat chamber is supported. In the arm 2 is formed a high pressure supply chamber 4 having a pipe connection with the source of steam supply, and a low pressure steam chamber 5, from which a conduit leads to the heating system within the car. The port 6 between the chambers 4 and 5 has a valve seat 7 at its outlet end, with which cooperates a movable valve member 8 carried by valve stem 9 which projects through a packing 10 in one end of low pressure chamber 5. A strainer 11 within the high pressure chamber 4 is held in place by a closure plug 4'.

95 A bell-crank lever 12 pivoted at 13 on a fixed bracket 14 formed on frame 1 has a pin and slot connection at 15 with one end of the valve stem 9, and its other arm is pivotally connected at 16 with the upper end of an op-

erating rod 17, which projects down through opening 18 into the chamber 19 formed in horizontal arm 3 of the main frame 1. A removable guard or casing 20 serves to shield 6 and protect the lever mechanism connecting operating rod 17 with the valve stem 9.

A return pipe from the radiators within the car is connected into an inlet port 21 leading into chamber 19, a similar alternative inlet port in the opposite side of the arm 3 being closed by a plug 22. An outer tube 23 and an inner tube 24 are respectively secured at their upper ends to and supported from the arm 3. The condensate flowing in from 10 the heating system through port 21 drains down through the annular space 25 formed between the inner and outer tubes 24 and 23, as indicated by the arrow *a* in Fig. 2. The greater portion of the returned steam or hot 15 gases flow down through the inner tube 24, as indicated by the arrow *b*.

The lower ends of the tubes 23 and 24 are connected with a lower bell-shaped casting 26. The inner tube 24 leads into a thermostatic 20 housing chamber 27 which is entirely closed, except for the open lower end and for the connection in the upper end with tube 24. The annular space 25 between the tubes 23 and 24 connects with a pair of drain passages 28 25 formed outside of the thermostat chamber 27. A removable closure member, indicated as a whole at 27^a, is removably secured to the lower end of the housing 26 so as to substantially close the thermostat chamber 27 30 except for a restricted outlet passage for the fluids returned to said chamber from the heating system. An adjusting screw 29 mounted in said closure member carries a head or rest 29^a at its upper end, upon which 35 is supported the thermostatic disc 30. A head 31 formed at the lower end of operating rod 17 contacts with the upper side of the thermostatic disc 30. A plurality of rounded projections 32 formed on the respective sides of 40 rod or stem 17 serve to loosely guide this rod for its vertical movements through inner tube 24. The rod 17 is so formed as to offer as little resistance as possible to the flow of 45 fluids through the tube 24 into the chamber 27. 50 All of the above noted structure is substantially well known in the art, except for the specific form of the closure 27^a and parts carried thereby, as will be hereinafter described. The vapor regulator operates in a 55 well known manner. When the thermostatic disc 30 is in its collapsed condition (as shown in the drawings), the valve 8 will be opened and steam will flow from supply chamber 4 into the low pressure chamber 5 and thence 60 to the radiators of the heating system. When the system has become filled with steam or vapor, the excess hot gases will flow through the return pipe from the system into the chamber 19, thence down through the inner tube 24 into housing 27 and will raise 65

the temperature of the thermostatic disc 30 and the thermostatic fluid contained therein, so that this disc will expand, lifting the operating rod 17, and moving bell-crank 12 and valve stem 9, thus closing the valve 8 70 against its seat 7 so as to cut off the further flow of steam or vapor to the radiators. Condensate from the radiators will drain down through the annular space 25 and passages 28. Any condensate forming in the housing 27 75 will flow out through the outlet passages, hereinafter described. As steam or vapor ceases to flow into the chamber 27 and the temperature of the gases in this chamber become lowered, the disc 30 will contract and 80 the valve 8 will again open, by virtue of the steam pressure from supply chamber 4, and a further supply of steam will flow to the radiators.

It will be noted that this vapor regulator 85 is supported beneath the car, so that the gases and condensate may escape through the lower end of the regulator. It is desirable that the thermostatic disc 30 be completely housed and protected as far as possible from the outer air 90 currents. In vapor regulators, as heretofore constructed, there is also a tendency for air to flow into the thermostat chamber through the outlet passages necessarily provided in the lower end thereof, thus interfering with 95 the proper functioning of this disc in direct response to the changing temperatures of the fluids returned from the radiating system. The particular object of the present invention is to provide an improved means for 100 more completely enclosing the thermostat, and preventing the flow of outer air into the thermostat chamber. The closure member 27^a is formed with a flat horizontally extending shoulder 33 adapted to bear against the lower edges of the skirt portion 34 of the thermostat housing, and is also formed with an annular upwardly extending flange portion 35 adapted to fit within the lower portion 105 of the housing. A hinge lug 36 extending from one side of the closure member is pivoted between a pair of hinge ears 37 on the housing 26, by means of hinge pin 37^a. At the opposite side of the closure a locking bolt 38 is pivoted on pin 39 between a pair of ears 40 formed in lug 41 on the closure. On the free threaded end 42 of bolt 38 is mounted 110 a thumb nut 43 adapted to clamp a loose washer or rider 44 above a pair of lugs or ears 45 formed on the housing 26.

A rather small centrally positioned outlet passage 46 formed in the closure member 27^a leads down into a shallow interior chamber 47. Below the chamber 47 a deflecting flange 48 curves downwardly and inwardly. Within the flange 48 is formed a supporting spider comprising a central disc 49 connected by radially extending legs 50 with the interior of flange 48 so as to provide a plurality of 115 downwardly and inwardly curving outlet 120 125 130

passages 51, leading from shallow chamber 47 to the outer air. An exteriorly and interiorly threaded bushing or plug 52 is threaded into a central opening provided in disc 49 and is locked in place by pin 53. The supporting and adjusting screw 29 for the thermostatic disc 30 is mounted in bushing 52 and is secured in adjusted position by means of lock nut 54. Screw 29 has a head or nut 55 formed on its lower end, by means of which the screw can be adjusted vertically. A plurality of lugs or shoulders 56 are formed within the shallow chamber enclosed by vertical flange 35 in order to limit the downward movement of the thermostatic disc 30. A plurality of hooks 57 project upwardly from the flange 35 of closure 27 to loosely engage over the upper side of thermostatic disc or diaphragm 30.

It will be noted that when the vapor regulator is assembled in operative position, as shown in the drawings, the thermostat member 30 will be clamped between the head or rest 29^a at the upper end of adjusting screw 29 and the similar head 31 formed on the lower end of operating rod 17. The thermostatic member will not ordinarily engage with either the lugs 56 or the hooks 57, but will be freely suspended therebetween. In case it should become necessary to inspect the parts or to replace the thermostatic member, the closure 27^a may be swung down about its pivot 37^a by merely loosening the thumb nut 43 and swinging locking bolt 38 from between the lugs 45. When the closure is swung downwardly away from the operating rod 17, the thermostatic disc 30 will be held in place between the hooks 57 and lugs 56, but may be freely withdrawn or lifted out at the side toward the hinge lug 36, as will be apparent from an inspection of the drawings.

The gases and such condensate as forms in chamber 27, can flow out through outlet passage 46, shallow chamber 47, and outlet passages 51. It will be noted that the thermostatic member is entirely enclosed within chamber 27 except for these outlet passages which are circuitous and not adapted to encourage the inflow of outer air to the chamber 27. Furthermore, the deflecting flange 48, which extends inwardly and downwardly and has an outer concaved surface, will deflect the surrounding air currents downwardly, particularly when the car is in motion, so as to create a partial vacuum beneath the outlets, thus causing a suction from the chamber 27. It is not desirable to have a strong suction or rapid withdrawal of fluids from chamber 27, and the deflecting flange 48 is not designed to produce a strong suction, but just sufficient suction to overcome any tendency of the outer air currents to flow into the housing and thus disturb the proper temperature conditions existing therein. It is

desirable that substantially all of the fluids in chamber 27 come from the radiating system, so that the thermostatic member 30 may respond promptly and accurately to the temperate conditions existing in the heating system. The greater portion of the condensate contained in the fluids flowing out of the radiators will drain out through the outer passages 25 and 28, and substantially nothing but gases and vapor will be returned to the chamber 27 in which the thermostat is located. If there is a high percentage of steam or vapor in these gases, so as to cause the disc 30 to expand and close the valve 8, this steam will eventually condense to form a liquid, which will drain out through the outlet passages inclosure 27, as hereinabove described.

I claim:

1. In a vapor regulator for railway car steam heating systems, a closed housing supported outside the car, a thermostatic member mounted within the housing and protected thereby, means for delivering fluids from the heating system into the housing, a fluid outlet in the lower end of the housing, and an annular flange projecting downwardly and inwardly around the outlet to induce an outward suction through the outlet.

2. In a vapor regulator for railway car steam heating systems, a closed housing supported outside the car, a thermostatic member mounted within the housing and protected thereby, means for delivering fluids from the heating system into the housing, a fluid outlet in the lower end of the housing, and an annular outwardly concaved flange projecting downwardly about the outlet to induce an outward suction through the outlet.

3. In a vapor regulator for railway car steam heating systems, a closed housing supported outside the car, a thermostatic member mounted within the housing and protected thereby, means for delivering fluids from the heating system into the housing, a closure for the lower end of the housing, supporting means mounted centrally in the closure for adjustably supporting the thermostatic member, a plurality of downwardly directed outlet passages extending through the closure and spaced around the supporting means, and an air deflector projecting downwardly from the closure for inducing an outward suction through the outlets.

4. In a vapor regulator for railway car steam heating systems, a closed housing supported outside the car, a thermostatic member mounted within the housing and protected thereby, means for delivering fluids from the heating system into the housing, a closure for the lower end of the housing, supporting means mounted centrally in the closure for adjustably supporting the thermostatic member, a plurality of downwardly directed outlet passages extending through the closure

and spaced around the supporting means, and an annular flange formed on the closure and projecting downwardly and inwardly around the outlets for inducing an outward suction through the outlets.

5. In a vapor regulator for railway car steam heating systems, a closed housing supported outside the car, a thermostatic member mounted within the housing and protected thereby, means for delivering fluids from the heating system into the housing, a closure for the lower end of the housing, supporting means mounted centrally in the closure for adjustably supporting the thermostatic member, a plurality of downwardly directed outlet passages extending through the closure and spaced around the supporting means, and an annular outwardly concaved flange projecting downwardly around the outlets for inducing an outward suction through the outlets.

6. In a vapor regulator for railway car steam heating systems, a closed housing supported outside the car, a thermostatic member mounted within the housing and protected thereby, means for delivering fluids from the heating system into the housing, a closure for the lower end of the housing, there being a central outlet passage in the closure, a downwardly and inwardly projecting flange extending from the closure around the outlet passage, a spider formed within the flange, an adjusting screw mounted in the spider and projecting centrally upward through the passage, and means at the upper end of the screw for supporting the thermostatic member.

7. In a vapor regulator for railway car steam heating systems, a closed housing supported outside the car, a thermostatic member mounted within the housing and protected thereby, means for delivering fluids from the heating system into the housing, a closure for the lower end of the housing, there being a central outlet passage in the closure, a downwardly and inwardly projecting flange extending from the closure around the outlet passage, a spider formed within the flange, an adjusting screw mounted in the spider and projecting centrally upward through the passage, and means at the upper end of the screw for supporting the thermostatic member, the outer surface of the flange being concaved to deflect air downwardly and thus create an outward suction through the outlet passage.

8. A vapor regulator for railway car heating systems comprising a supporting housing, said housing formed with a high pressure inlet chamber, a low pressure outlet chamber, and a steam passage between the chambers, a valve for opening or closing the passage, a thermostatic member, operating connections between the thermostatic member and the valve, the housing being formed with a vertically disposed closed chamber in which the thermostatic member is supported and

protected, an inlet to the upper end of this last mentioned chamber for fluids returned from the heating system, a closure for the lower end of this chamber, a fluid outlet therein, and an annular deflecting flange extending downwardly and inwardly around the outlet.

9. A vapor regulator for railway car heating systems comprising a supporting housing, said housing formed with a high pressure inlet chamber, a low pressure outlet chamber, and a steam passage between the chambers, a valve for opening or closing the passage, a thermostatic member, operating connections between the thermostatic member and the valve, the housing being formed with a vertically disposed closed chamber in which the thermostatic member is supported and protected, an inlet to the upper end of this last mentioned chamber for fluids returned from the heating system, a closure for the lower end of this chamber, a fluid outlet therein, and an outwardly concaved flange projecting downwardly around the outlet.

10. A vapor regulator for railway car heating systems comprising a supporting housing, said housing formed with a high pressure inlet chamber, a low pressure outlet chamber, and a steam passage between the chambers, a valve for opening or closing the passage, a thermostatic member, operating connections between the thermostatic member and the valve, the housing being formed with a vertically disposed closed chamber in which the thermostatic member is supported and protected, an inlet to the upper end of this last mentioned chamber for fluids returned from the heating system, a closure for the lower end of this chamber, there being a central outlet passage in the closure, a downwardly and inwardly projecting deflecting flange extending from the closure around the outlet, a spider formed within the flange with a central body portion beneath the outlet and a series of passages leading from the outlet around the central body, an adjusting screw mounted in the spider and projecting centrally upward through the outlet opening and means at the upper end of the screw for supporting the thermostatic member.

11. A vapor regulator for railway car heating systems comprising a supporting housing, said housing formed with a high pressure inlet chamber, a low pressure outlet chamber, and a steam passage between the chambers, a valve for opening or closing the passage, a thermostatic member, operating connections between the thermostatic member and the valve, the housing being formed with a vertically disposed closed chamber in which the thermostatic member is supported and protected, an inlet to the upper end of this last mentioned chamber for fluids returned from the heating system, a closure for the lower end of this chamber, there being a central outlet

passage in the closure, a downwardly and inwardly projecting deflecting flange extending from the closure around the outlet, a spider formed within the flange with a central body portion beneath the outlet and a series of passages leading from the outlet around the central body, an adjusting screw mounted in the spider and projecting centrally upward through the outlet opening and means at the upper end of the screw for supporting the thermostatic member, the outer surface of the flange being concaved to deflect air downwardly and create an outward suction through the outlet passage.

12. A vapor regulator for railway car heating systems comprising a supporting housing, said housing being formed with a high pressure inlet chamber, a low pressure outlet chamber, and a steam passage between the chambers, a valve for opening or closing the passage, a thermostatic member, operating connections between the thermostatic member and the valve, the housing being formed with a vertically disposed bell-shaped housing in which the thermostatic member is enclosed, said housing having an inlet in its upper end for the fluids returned from the heating system, a closure member removably secured to the lower end of the housing, said closure having a central outlet passage, a downwardly and inwardly projecting deflecting flange extending from the closure around the outlet, a spider formed within the deflecting flange, an adjusting screw mounted centrally within the spider and projecting up through the outlet passage, means at the upper end of the screw for supporting the thermostatic member, and means on the closure and loosely engaging about the thermostatic member to support the member when the closure is removed from its normal engagement with the bottom of the thermostat housing.

EDWARD A. RUSSELL.
